UNITED STATES PATENT OFFICE.

ERIC A. STARKE, OF BERKELEY, CALIFORNIA.

RECOVERING GASOLINE FROM NATURAL GAS.

Application filed September 12, 1921. Serial No. 499,988.

To all whom it may concern:

Be it known that I, ERIC A. STARKE, a citizen of the United States, residing at Berkeley, in the county of Alameda and State of California, have invented certain new and useful Improvements in Recovering Gasoline from Natural Gas, of which the following is a specification.

My invention relates to the art of recovering gasoline from a hydrocarbon gas, such, for example, as natural gas, by the absorption method.

The object of my invention is to provide for a thorough mechanical mixing of the gas and oil to facilitate the absorption, and to this end my invention consists in the novel apparatus which I shall now fully describe, by reference to the accompanying drawing, in which the figure is a general view of my apparatus.

1 is a tank to contain the absorbing oil. 2 is an outlet pipe from the tank, leading to the suction side of a centrifugal pump 3, the casing or shell of which I have here shown broken away, to show its internal rotatable impeller 3'. 4 is a pipe leading from a suitable source of a hydrocarbon gas, and communicating with the outlet pipe 2 from tank 1.

5 is a pipe leading from the discharge side of the centrifugal pump 3 to a separator. This separator may be of any suitable character, but for the sake of illustration I have herein shown it as comprising a plurality of elongated, recumbent vessels 6, with the first of which the pipe 5 communicates. These vessels communicate successively, from the top of one to the bottom of the next, by pipe 7, at intervals, the last vessel having a pipe 8 with pressure valve 8', leading from its upper cross-sectional area for the discharge of the non-absorbed residual gas. From the lower cross sectional area of each separator vessel leads a pipe 9 to a pipe 10 which leads back to the tank 1. Thus a closed circuit is provided throughout all the elements of the apparatus.

In operation, the absorbing oil and the hydrocarbon gas are introduced together, to the suction side of the centrifugal pump.

By reason of the structure of such a pump, comprising the high speed impeller 3' therein, the oil and gas are thoroughly mixed, and the necessary circulation, under pressure, maintained.

In the separator vessels, the gaseous component of the mixture is separated from the liquid component and is carried off, while the liquid component is returned to the tank. As is usual in this art, the enriched oil is taken from the tank, as, for example, by a pipe 11, to a still 12, and after distillation the impoverished oil is carried back from the still by a pump 13 through a pipe 14 into the tank 1, thereby returning absorbing oil to the system.

I claim:

1. An apparatus for the described purpose comprising, in a closed circuit, a centrifugal pump; means for introducing absorbing oil together with a hydrocarbon gas, to the suction side of said pump; a plurality of elongated, recumbent vessels communicating successively at intervals from the top cross sectional area of one to the bottom cross sectional area of the next; a pipe leading from the discharge side of the centrifugal pump to the bottom cross sectional area of the first of said vessels; means for discharging the non-absorbed residual gas from the top cross sectional area of the last of said vessels; a still; means for conveying the enriched oil from the bottom cross sectional areas of all of said vessels to the still; and means for returning the impoverished oil from the still to the absorbing oil introducing means connected with the suction side of the pump.

2. An apparatus for the described purpose comprising, in a closed circuit, a centrifugal pump; a tank for the absorbing oil; a connection from a source of hydrocarbon gas; means for introducing the gas from said source connection, together with the oil from said tank, to the suction side of the pump; a plurality of elongated, recumbent vessels communicating successively at intervals from the top cross sectional area of one to the bottom cross sectional area of the next; a pipe leading from the discharge side

of the centrifugal pump to the bottom cross sectional area of the first of said vessels; means for discharging the non-absorbed residual gas from the top cross sectional area of the last of said vessels; means for conveying the enriched oil from the bottom cross sectional areas of all of said vessels

to the tank; a still; a connection for conveying the oil from the tank to the still; and a connection for returning the impoverished oil from the still to the tank.

In testimony whereof I have signed my name to this specification.

ERIC A. STARKE.
